Primary Examiner — Jae Liang(74) *Attorney, Agent, or Firm* — Kirk A. Buhler; Buhler & Associates Patenting(57) **CLAIM**

The ornamental design for a shaker cup, as shown.

DESCRIPTION

FIG. 1 is a top rear perspective view of a shaker cup, showing my new design;

FIG. 2 is a rear elevation view thereof;

FIG. 3 is a front elevation view thereof;

FIG. 4 is a left side elevation view, the right-side elevation view being a mirror image thereof, and,

FIG. 5 is a top plan view thereof;

FIG. 6 is a bottom view thereof;

FIG. 7 is a right side sectional view taken along lines 7-7 from FIG. 3 thereof; and,

FIG. 8 is an exploded top rear perspective view.
